DESIGN FOR A BELT

Sam Platt, Brooklyn, N. Y.

Application June 12, 1946, Serial No. 130,651

Term of patent 3½ years

(Cl. D3—10)

To all whom it may concern:

Be it known that I, Sam Platt, a citizen of the United States, residing at Brooklyn, New York, in the county of Kings and State of New York, have invented a new, original, and ornamental Design for a Belt, of which the following is a specification, reference being had to the accompanying drawing, forming a part thereof:

In the drawing:

Fig. 1 is a front perspective view of a belt, showing my new design;

Fig. 2 is a rear elevational view; and

Fig. 3 is a side elevational view of the same.

I claim:

The ornamental design for a belt, as shown.

SAM PLATT.
